CLAIM

The ornamental design for a shoe, as shown and described.

DESCRIPTION

FIG. 1 is a perspective view of a shoe, showing the new
design;

FIG. 2 is a medial side view thereof;

FIG. 3 is a lateral side view thereof; and,

FIG. 4 is a top view thereof.

The broken lines shown in the drawings illustrate portions of
the shoe that form no part of the claimed design. The
unshaded surfaces form no part of the claimed design.
A left-foot shoe is illustrated in FIGS. 1-4. A second embodiment
of the design includes a right-foot shoe, which is a
mirror image of the views of the first embodiment.
